GAETANO ARTURO CROCCO, OF ROME, ITALY.

SEMIRIGID AIRSHIP.

Application filed September 26, 1922. Serial No. 590,676.

To all whom it may concern:

Be it known that I, GAETANO ARTURO Crocco, a subject of the King of Italy, residing at Rome, in the Kingdom of Italy, have invented certain new and useful Improvements in Semirigid Airships, of which the following is a specification.

The semirigid airships wherein the bending and cutting stresses of the loads are borne by a stiff lower frame owing to this fact lose the chief advantage of their type, i.e. their flexibility, and the stiff frame when the airship is travelling in exceptionally bad weather, if even momentary, is subject to break towards its middle.

In order to avoid this inconvenience one or more articulations may be provided in the lower frame, where the bending stresses due to statical loads are on the average of little importance and leave the points where the joints are to bear the dynamic loads and the occasional statical overloads by the natural resistance of the envelope under pressure.

This can be done without any special change in the frames now-a-days used for semirigid airships, if the airship is allowed, under the action of these dynamic loads or statical overloads, to deform freely in its longitudinal line, owing to the elasticity of the cloth whereof it is made.

In such case, however, said deformation, though it occurs gradually and steadily, has the inconvenience to lessen the penetrating quality of the airship and introduce dynamic perturbating actions.

Thus is it necessary to eliminate it, or at least reduce it to be practically of little value; and this invention has for its object structural arrangements designed in view of securing the aforesaid result.

They consist substantially in rope connections of the hinged sections carried out by connecting the ascensional forces acting on the back of the envelope, as it will be better hereunder explained with reference to the appended drawings wherein:

Figs. 1 and 2 respectively show in transverse and in a longitudinal section an airship with connections of the lower beam and the back of the envelope;

Fig. 3 shows in a longitudinal section an airship in accordance with the invention with a lower beam with a central hinge, and an upturned catenary as in a suspension

bridge connecting the beam with the back of the gas bag;

Fig. 4 shows a longitudinal section of another airship also with a single central hinge for the beam, but with two catenaries instead of one;

Fig. 5 shows, also in a longitudinal section, an airship with a double hinge beam, and with two crossing catenaries;

Figs. 6 and 7 show details of the catenary attachments.

Assume, by way of instance, it is proposed to render indeformable an airship of the Italian type, in which the ascensional force is transmitted to a lower beam not only by means of the tension of the cloth of the gas bag on the sides, but also by means of rope connections with the back, as shown in Figs. 1 and 2.

In both figures, 1, 1, 1, is a rigid frame which, by way of example has been illustrated as a triangular beam; 2, 2, are the sides of the envelope which transmit to it partially the lifting power; 3, 3, 3 are rope connections which collect the lifting power on the back of a section and transmit it by means of ropes 4, 4, 4 to the beam underneath.

Now by introducing (Fig. 3) a hinge 5 towards the middle of the beam and connecting with catenaries in an inverted suspension bridge a part of the lifting power of the ropes 4, shows in the foregoing figures, it will be understood how, by suitably choosing the extreme points of attachment 7 of the catenary and the positions of the loads 8, the bending moment due to said loads, to the reactions of the catenary in the points 7, and to the residual lifting powers transmitted to the beam by the ropes 4, can be made to vanish.

In this arrangement of things it is of course necessary not to balance with the catenary all the lifting power of the ropes 4, and to leave a residual part so as to allow the catenary to eventually be able to develop a greater tension without its attachment points at the ropes 4 giving away.

This happens precisely when through dynamic actions or through statical overloads, in the two sections of the beam, on both sides of the hinge, develop forces in a downward direction which by acting on the connection points 7 of the catenary increase its tension and therefore take up a larger portion of

the lifting forces of 4. It will be understood how, within the limits of such lifting forces, the system thus constituted will not be appreciably deformed, and acquires therefore 5 the capacity of sustaining eventual loads in the direction as indicated.

It will be also evident how the system lends itself to resist without deformation the action of eventual loads in the opposite 10 direction, viz: in an upward direction.

In such case the tension of the catenary diminishes and therefore the ropes 4 increase, to the utmost, the residual lifting 15 power transmitted to the beam; and the limit of indeformability is exactly this maximum which corresponds to the vanishing of the catenary tension.

The rope connections above described secure therefore the indeformability of the 20 whole structure of catenary and hinged beam, and hence of all the envelope.

It possesses also the advantage of lessening the weight of the beam, for it substitutes to the flat beam an element of greater 25 height in resisting to a part of the stresses of permanent loads.

Instead of only one catenary, two as 6 and 9 in Fig. 4 and even more might be provided and the beam might have two or 30 more hinged joints, 11, 12 with crossed catenaries 13, 13 as in Fig. 5, differently connected with one another, according to the opportunities resulting in each case from the distribution of the loads.

35 The details of the connections of the catenaries with the ropes 4 are illustrated by way of example in Figs. 6 and 7.

The vertical ropes 4, double or single, carry an eyelet 19 within which runs the 40 rope 6 of the catenary. The sliding movement of this rope is prevented by stays 16 adhering to the rope. A little adherence will suffice because the differential tensions of the rope 6 are a small part of the required tension.

45 The structure above described constitutes a new type of stiffening in airships wherein the envelope concurs to bear the bending stresses of the loads. The upper catenary

tension and the corresponding compression 50 of the lower beam resist in every section the statical or dynamical flections of the loads, forming a true resisting beam with member distant one from the other about the diameter of the section, and therefore 55 in the best geometrical conditions to obtain the utmost lightness.

Claims—

1. In semirigid airships with a lower frame comprising a plurality of rigid sections, hinges connecting said sections, and substantially vertical rope connections between said sections and the top of the envelope where the vertical ropes are fastened by means of small catenaries, catenary connections in the shape of an inverted suspension bridge between a plurality of said vertical ropes, and which collect the lifting power from the back of the envelope and transmit it to the rigid sections of the lower 70 frame where their ends are fastened. 65

2. In semirigid airships of the class as specified in claim 1 and in which the lower frame comprises two hinged rigid sections, a single large catenary connecting the vertical ropes and fastened at each of its ends to one of the sections of the lower frame. 75

3. In semirigid airships of the class as specified in claim 1 and in which the lower frame comprises two hinged rigid sections, 80 a plurality of catenaries connecting the vertical ropes and fastened at their ends to each of the said two sections.

4. In semirigid airships of the class as specified in claim 1 and with a lower rigid 85 frame comprising three hinged sections, catenaries connecting the vertical ropes, each catenary fastened at its both ends to two of the hinged sections.

In testimony whereof I have signed my 90 name in the presence of two subscribing witnesses at Rome in the Kingdom of Italy this 7th day of September, 1922.
